(No Model.)

O. STERNOFF-BEYER.
DRILLING MACHINE.

No. 479,086.

Patented July 19, 1892.

UNITED STATES PATENT OFFICE.

OTTO STERNOFF-BEYER, OF CARLSTADT, NEW JERSEY, ASSIGNOR TO BÖHM BROTHERS, OF NEW YORK, N. Y.

DRILLING-MACHINE.

SPECIFICATION forming part of Letters Patent No. 479,086, dated July 19, 1892.

Application filed September 26, 1891. Serial No. 406,881. (No model.)

To all whom it may concern:

Be it known that I, OTTO STERNOFF-BEYER, of Carlstadt, in the county of Bergen and State of New Jersey, have invented a new and Improved Drilling-Machine, of which the following is a full, clear, and exact description.

The invention relates to multiple drilling-machines for drilling a series of apertures in buttons or other like articles.

The object of the invention is to provide an improved drilling-machine, which is simple and durable in construction, very effective in operation, and designed to accurately drill a series of symmetrically-arranged apertures in the article.

The invention consists of a series of similarly-revolving drills arranged in a circle, but eccentric to the centers of the articles to be drilled.

The invention further consists of a revolvable disk adapted to support a series of articles to be drilled and arranged opposite a series of similarly-revolving drills arranged in a circle and eccentric to the articles held by the said disk.

The invention also consists of certain parts and details and combinations of the same, as will be fully described hereinafter, and then pointed out in the claims.

Reference is to be had to the accompanying drawings, forming a part of this specification, in which similar letters and numerals of reference indicate corresponding parts in all the figures.

Figure 1 is a side elevation of the improvement with parts in section. Fig. 2 is a transverse section of the same on the line $x-x$ of Fig. 1. Fig. 3 is a similar view of the same on the line $y-y$ of Fig. 1, and Fig. 4 is a like view of the same on the line $z-z$ of Fig. 1.

The improved drilling-machine is provided with a base A, supporting on one end a head-stock B, in which are journaled a series of drill-spindles C, C', C², and C³, arranged in a circle, as is plainly indicated in Fig. 2. The drill-spindles support suitable drills D, D', D², and D³, respectively, and on the said spindles within the head-stock B are secured gear-wheels E, E', E², and E³, respectively, all

in mesh with a centrally-arranged gear-wheel F, secured on a driving-shaft G, mounted to turn in suitable bearings in the head-stock B and connected with suitable machinery for imparting a rotary motion to the said shaft G, and by the gear-wheels F, E, E', E², and E³ to the drill-spindles and the drills, so that the latter rotate simultaneously.

On the base A, opposite the drills D, D', D², and D³, is arranged a disk or wheel H, secured on a shaft I, mounted to turn and to slide in suitable bearings held on a frame J, supported on the base A. On the outer end of the shaft I is secured a knob I' for conveniently turning the said shaft for imparting a sliding motion to the same, for the purpose hereinafter more fully described.

On the wheel or disk H is arranged a series of chucks K, K', K², and K³, arranged in a circle which is eccentric to the circle in which the drills D, D', D², and D³ are located. Each of the chucks K, K', K², or K³ is made conical and split into sections forming jaws, the conical part fitting into a correspondingly-shaped recess extending longitudinally in the wheel H. When a chuck is pushed out of its seat in the wheel H, then the split sections open to permit ready displacement of the article held in a recess in the front end of the respective chuck and also permit of conveniently inserting a new article to be drilled.

In order to hold a chuck K, K', K², or K³ in position, a spring L engages the rear end of the chuck and presses at one end against the rear face of the wheel H and with its other end on a pin L', secured to the projecting end of the chuck.

On one side of the frame J is arranged a lug N, adapted to be engaged by the rear end of a chuck when the shaft I is slid rearward, so that the respective chuck is pressed on and pushed out of its seat in the wheel H to permit its split sections to open to release the article therein and to permit of inserting a new article. As soon as the shaft is moved forward, the respective spring L on the chuck again forces the latter to its seat in the wheel.

The wheel H is provided with an annular flange O, formed with a series of recesses O', O², O³, and O⁴, arranged in line with the chucks

K, K', K², and K³, respectively, and adapted to be alternately engaged by the wedge-shaped part P' of a lever P, pivoted to the frame J and held in a locked position by a 5 spring Q, as is plainly shown in Fig. 1. The lever P extends longitudinally and permits the wheel H to slide longitudinally when the shaft I is pulled, and the wedge-shaped part P' permits of turning the wheel H in one direction when the position of the chucks is to be changed, for the purpose presently to be stated.

The operation is as follows: When the wheel H is in the position illustrated in Fig. 3 and 15 the several chucks K, K', K², and K³ are empty, then the operator, in order to start the machine, pulls on the knob I', so that the wheel H moves rearward and the chuck K is opened by abutting on the projection N. A blank 20 button can then be readily inserted into the open chuck K, after which the operator releases the pressure on the knob I', so that the spring L on the chuck K forces the latter back to its seat in the wheel H, thereby closing the 25 jaws and thus securely holding the button in place. The operator then gives a quarter-turn to the knob I', so that the wheel H turns and moves the chuck K opposite the drill D', the position of the other chucks being correspondingly changed relative to the drills. 30 The operator now pushes on the knob I', so that the shaft I, with the wheel H and the chucks, is moved toward the head-stock B and the revolving drill D' drills an opening in the 35 button at one side of its center at 1, as plainly shown in Fig. 3. As soon as the aperture has been drilled the operator pulls on the knob I', so as to return the wheel H to the position shown in Fig. 1. A farther rearward pull 40 brings the second chuck K³ in contact with the projection N, so that this chuck K³ opens and the button is inserted therein. The operator then gives a quarter-turn to the knob I' and consequently to the shaft I and wheel 45 H, so that the chuck K is moved opposite the drill D² and the chuck K³ is moved opposite the drill D'. A farther forward movement of the wheel H causes the drills D' and D² to 50 drill apertures in the buttons held in the chuck K and K³, the aperture in the button of the chuck K being to one side of its center alongside the aperture 1, as illustrated at the left in Fig. 3, the second aperture being indicated by the numeral 2. An aperture is also 55 drilled in the button in the chuck K³ at 1, as shown in the said figure. A rearward pull on the knob I' moves the wheel H back to its normal position, and a farther rearward pull brings the chuck K² in contact with the projection N, so that the chuck-jaws are opened 60 and a button can be inserted. After the button is locked in the jaws of the chuck K² the wheel H is again given a quarter-turn, so that the first chuck K is opposite the drill D³, the chuck K³ is opposite the drill D², and the chuck K² is opposite the drill D', while the chuck K' is opposite the drill D. By

pushing the wheel H forward three apertures are drilled in the three buttons, the aperture in the button of the chuck K being 70 drilled at 3 alongside the other two apertures 1 and 2, and at one side of the center of the button, as shown at the bottom of the wheel in Fig. 3. The second aperture is drilled in the button in the chuck K³, while 75 the first aperture is drilled in the button in the chuck K². After the apertures are drilled the wheel K is moved backward until the 80 jaws in the chuck K' open for the insertion of a button in the said chuck. The wheel H is then again given a quarter-turn, so that the several chucks assume the position illustrated in Fig. 3, and then on the forward movement of the wheel H toward the head-stock B four apertures are drilled in the four buttons— 85 namely, one aperture in the button in the chuck K at 1, two apertures in the button in the chuck K², (marked 1 and 2,) three apertures in the button in the chuck K³, (indicated by the numerals 1, 2, and 3,) and four 90 apertures in the button in the chuck K, (marked 1, 2, 3, and 4.) On a farther rearward movement of the wheel H the chuck K is brought in contact with the projection N, so that the jaws open and the button with the 95 four apertures drilled in it drops out of the jaws and a new button is inserted. The above-described operation is then repeated—that is, a quarter-turn is given to the wheel H, and it is then moved forward toward the 100 head-stock B—so that four apertures are drilled in the four buttons in the manner above described.

It is understood that the wheel H is locked in position after the quarter-turns have been 105 given to it in the manner above described by the lever P dropping in the respective notches O', O⁴, O³, and O², formed in the flange O of the said wheel. The wheel is always turned at the time the flange O stands under the incline P', as the latter permits turning of the 110 said wheel by the incline sliding out of the notch and the lever resting on the flange O until it again drops into the next following notch. The lever is sufficiently long to permit a forward and backward sliding of the wheel H without the said lever becoming disconnected from the respective notch during the longitudinal movement. It will be seen that when the wheel H is revolved or given a 115 quarter-turn, as above described, each button changes position relative to the next drill, so that the four apertures are drilled in the button in a circle after four quarter-turns have 120 been made, each button being operated on by 125 each one of the drills, which are arranged in a circle eccentric to the circle in which the buttons are located.

It is understood that the device can be readily arranged for drilling two, three, five, six, 130 or any number of articles with a corresponding number of apertures, the wheel H being provided for this purpose with a corresponding number of chucks and the head-stock B

being provided with a corresponding number of drills arranged in a circle eccentric to the circle in which the chucks are located in the wheel H.

5 Having thus described my invention, I claim as new and desire to secure by Letters Patent—

1. A drilling-machine provided with a series of simultaneously-revolving drills arranged 10 in a circle and eccentric to the axis of the article-supporting devices, substantially as shown and described.

2. A drilling-machine comprising a disk carrying a series of article-supporting devices 15 arranged in a circle and a series of simultaneously-revolving drills arranged in a circle eccentric to the circle in which the article-supporting devices are arranged, substantially as shown and described.

20 3. A drilling-machine comprising a series of simultaneously-revolving drills arranged in a circle and a series of chucks for supporting the article to be drilled and arranged in a circle eccentric to the circle in which the 25 drills are arranged, substantially as shown and described.

4. A drilling-machine provided with a wheel mounted to turn and to slide and a series of spring-pressed chucks arranged in a circle on 30 the said wheel and formed with split sections, and a recess to centrally support the article to be drilled, substantially as shown and described.

5. A drilling-machine provided with a wheel 35 mounted to turn and to slide, a series of spring-pressed chucks arranged in a circle on the said wheel and formed with split sections,

and a recess to centrally support the article to be drilled, and a fixed lug adapted to engage the chuck to open the latter, substantially 40 as shown and described.

6. In a drilling-machine, the combination, with a series of simultaneously-revolving drills arranged in a circle, of a wheel mounted to slide and to turn and arranged opposite 45 but eccentric to the said drills and chucks arranged in a circle on the said wheel and adapted to support centrally the articles to be drilled, substantially as shown and described.

7. In a drilling-machine, the combination, 50 with a series of simultaneously-revolving drills arranged in a circle, of a wheel mounted to slide and to turn and arranged opposite but eccentric to the said drills, chucks arranged in a circle on the said wheel and adapted 55 to support centrally the articles to be drilled, and means, substantially as described, for opening and closing one of the chucks at a time, as set forth.

8. In a drilling-machine, the combination, 60 with a series of simultaneously-revolving drills arranged in a circle, of a wheel mounted to slide and to turn and arranged opposite but eccentric to the said drills, chucks arranged in a circle on the said wheel and adapted 65 to support centrally the articles to be drilled, and means, substantially as described, for holding the said wheel in position while sliding forward and backward, as set forth.

O. STERNOFF-BEYER.
